(57) **CLAIM**

The ornamental design for a display screen or portion thereof with animated graphical user interface for selective movement of a data table header, as shown and described.

DESCRIPTION

FIG. 1 is a front view of first image in a first embodiment of the sequence of a display screen or portion thereof with animated graphical user interface for selective movement of a data table header showing my new design;

FIG. 2 is a front view of a second image thereof;

FIG. 3 is a front view of a third image thereof;

FIG. 4 is a front view of a fourth image thereof;

FIG. 5 is a front view of a fifth image thereof; and

FIG. 6 is a front view of a sixth image thereof.

FIG. 7 is a front view of first image in a second embodiment of the sequence of a display screen or portion thereof with animated graphical user interface for selective movement of a data table header showing my new design;

FIG. 8 is a front view of a second image thereof;

FIG. 9 is a front view of a third image thereof;

FIG. 10 is a front view of a fourth image thereof;

FIG. 11 is a front view of a fifth image thereof; and,

FIG. 12 is a front view of a sixth image thereof.

The dash-dash broken lines showing portions of the graphical user interface form no part of the claimed design. The dot-dash broken lines showing the display screen or portion thereof form no part of the claimed design. The appearance of the animated images sequentially transition from FIG. 1 to FIG. 6 in the first embodiment, and FIG. 7 to FIG. 12 in the second embodiment. The process or period in which one image transitions to another forms no part of the claimed design.
